UNITED STATES PATENT OFFICE.

JOHN H. LYITLE AND JOHN J. McFARLAND, OF MILWAUKEE, WISCONSIN.

CARBURETER.

1,339,403.

Specification of Letters Patent. Patented May 11, 1920.

Application filed September 10, 1917. Serial No. 190,689.

To all whom it may concern:

Be it known that we, JOHN H. LYITLE and JOHN J. McFARLAND, both citizens of the United States, and residents of Milwaukee, 5 in the county of Milwaukee and State of Wisconsin, have invented certain new and useful Improvements in Carbureters; and we do hereby declare that the following is a full, clear, and exact description thereof.

10 The primary object of our invention is to provide a water jacket about the mixing chamber of that type of carbureter in which the heat from the exhaust manifold is utilized to expand the fuel gases. Heretofore it has been found in practice that when 15 the hot gases passing through the manifold come directly in contact with the metal wall of the mixing chamber, said mixing chamber will become overheated and cause pre- 20 ignition of the gases. Hence our invention is designed to overcome this objection to a type of carbureter which, with the exception mentioned, is a practical and economical device.

25 It is another object of the present invention to utilize the heat of the exhaust gases of the engine as a means for procuring a desired heating of the explosive mixture and it is more specifically an object to provide a simple carbureter structure wherein 30 the mixing chamber thereof is disposed in the path of the exhaust gases of the engine.

It is further an object to provide such a carbureting device which may be associated 35 with the exhaust and intake manifolds of an engine in a manner according with the general present design of multicylinder engine structures, and may comprise a relatively simple structure.

40 With the above and other objects and advantages in view the invention resides more particularly in the novel combination, arrangement and formation of parts more particularly hereinafter described and more 45 particularly pointed out in the appended claim.

In the drawings—

Figure 1 is an elevational view of the exhaust and intake manifolds of an engine 50 showing the improved carbureter device associated therewith.

Fig. 2 is a sectional view through the carbureter on the line 2—2 of Fig. 1.

Referring now more particularly to the 55 accompanying drawings, 5 designates the horizontal head portion of the exhaust

manifold of an engine which includes the central depending portion 6, and 7 designates the intake manifold which is disposed above the exhaust manifold and which in 60 the present instance is inwardly offset with respect thereto.

The exhaust manifold above its depending portion 6 is enlarged at 8 in the shape of a bowl and seated in this bowl shaped 65 enlargement is a jacket bowl 9 which is secured in place and held spaced from the walls of the enlargement by an annular flange 10 at its upper portion seated on and secured to a flange 10^a at the mouth of the 70 enlargement 8. Seated in the jacket bowl 9 is a mixing chamber bowl 11, spaced therefrom and preferably integrally connected at its mouth with the mouth of the jacket bowl whereby to form an inclosed water space. 75 Access to this water space is afforded through an opening in the mouth portion of the bowl 9 which is normally closed by the plug 9^b to thus seal the water space. The outer portion of the bowl 11 is provided with a 80 covering wall 12 and the inner portion of the bowl communicates with a depending portion 13 of the intake manifold.

A well 14 is formed in the cover wall 12 and the lower end of this well forms a valve 85 seat engageable by a valve head 15 which has its stem 16 extending upwardly through the well and carrying an expansile spring 17 which bears against an adjustable nut 18 on the stem and a spider 19 secured in 90 the mouth of the well. The lower end of the well wall is connected with the adjacent portion of the bowl 9 by an integral portion 20 and formed in this portion and in the adjacent bowl and well wall portions 95 is a fuel duct 21 which at one end communicates with the valve seat and which at its other end communicates with a nipple 22 passed through the bowl portion 8 and threaded in the bowl, 9. This nipple is 100 provided with an adjusting needle valve 23 to limit flow of fluid therethrough, and is connected with a float valve chamber 24.

Thus in the operation of the engine, the air and fuel fluid is drawn into the bowl 9 105 and properly mixed and at the same time heated whereby the vaporization of the fuel fluid is assured. Inasmuch as the mixing bowl is disposed at the meeting of the flow of exhaust gases, it is at all times subjected to a proper degree of heat. In some instances the degree of heat imparted to the

fluid in the mixing bowl would be so great as to cause an explosion of gas in this chamber, and to prevent the possibility of overheating, the wall of the bowl is formed in a 5 hollow manner to provide a water jacket for the mixing chamber.

After the engine has started, it is manifest that the exhaust gases will maintain the desired temperature and, owing to the water 10 jacket, there is no liability of the temperature increasing to such a degree as to cause preignition of the gases within the mixing chamber.

Inasmuch as the average temperature 15 present under running conditions in the bowl engaging portions of the exhaust gases is not sufficient to produce a dangerously excessive heat, no vent is shown for the water space of the jacket, although to meet 20 extreme conditions a pressure valve and feeding means may be employed. It is well known that in the ordinary operation of a motor vehicle, the temperature conditions and the flow of the exhaust gases varies considerably, and the flow is cut off entirely 25 during those intermittent periods which afford an opportunity to coast. When the engine is running at very high speed, or climbing a hill, a high temperature is present 30 and an excessive heat is applied to the bowl. Experience has also demonstrated to us that under coasting conditions the bowl and consequently the mixing chamber may become cooled to such extent as to prevent vaporization of the fuel and consequently prevent 35 starting the engine when the coasting period is ended without the application of some extraneous heating means or the use of higher grade fuel in the engine. The

function of our water jacket is to retain heat 40 during the coasting or idle periods, as well as to absorb heat during the high temperature conditions, and thus the water jacket serves to afford a balance in these variations of temperature conditions, wherein a proper 45 heat will be supplied at all times to the mixing chamber, it being noted that the maximum temperature is not sufficient to burn out the bowl.

We claim:

The combination with an engine including a horizontally extending intake manifold and an exhaust manifold disposed below the intake manifold and provided with an indeterminate depending discharge neck, of a 55 bowl shaped enlargement in the exhaust manifold above the discharge neck, a depending neck on the intake manifold above said enlargement of the exhaust manifold, a jacketed mixing bowl having its major 60 portion disposed in the enlargement of the exhaust manifold, the wall of the bowl being spaced from the wall of said enlargement, an outwardly extending flange on the mixing bowl secured to the enlargement in the 65 exhaust manifold and closing the same, the depending neck of the intake manifold closing the inner portion of the bowl, a cover for the outer portion of the bowl, a well carried by said cover and forming an air inlet 70 port, and a fuel inlet port adjacent the bottom portion of the well.

In testimony that we claim the foregoing we have hereunto set our hands at Milwaukee, in the county of Milwaukee and State 75 of Wisconsin.

JOHN H. LYTHE.
JOHN J. McFARLAND.
